UNITED STATES PATENT OFFICE.

ALFRED GRIEB, OF ELIZABETH, AND JOSEPH F. PALME, OF NEWARK, NEW JERSEY,
ASSIGNORS TO THE SINGER MANUFACTURING COMPANY, OF ELIZABETH, NEW
JERSEY, A CORPORATION OF NEW JERSEY.

OVEREDGE SEWING MACHINE.

Application filed September 27, 1923. Serial No. 665,059.

This invention relates to improvements in stitch-forming mechanisms for overedge sewing machines of the type wherein the thread carried by a work-penetrating eye-pointed needle is enchain'd along the margin of the work by a bearded needle.

The present invention has for an object to improve the efficiency of overedge sewing machines of this character by making possible a substantial increase in the speed of operation thereof under reasonably quiet running conditions.

Another object of this invention is to provide an overedging machine of this character capable of producing overseams varying in width of bight to a substantial degree.

In its preferred embodiment, the eye-pointed and bearded needles are carried in adjustably spaced relation by a reciprocatory needle-bar. Cooperating with the needles for carrying thread-loops above and below the work from the eye-pointed needle to the thread-enchaining bearded needle are independently actuated upper and lower loop-spreaders disposed respectively above and below the cloth-plate of the machine. The lower spreader has simple vibratory movements derived from a grooved cam-cylinder mounted upon the needle-driving shaft, the operative elements for actuating said lower spreader being capable of being connected in a plurality of predetermined positions to actuate said lower spreader in the necessary timed relationship with respect to its cooperating stitch-forming elements in the formation of a plurality of widths of bight of overseam. The upper spreader is sustained by a rocking carrier mounted upon a swinging arm of a bell-crank-lever, both the swinging movements of the arm and the rocking movements of the carrier upon said arm being derived in the present instance from cam-grooves in the lower-spreader actuating cam-cylinder.

The operation of the upper spreader can be definitely retimed for various widths of bight of overseam in a manner similar to that of the lower spreader.

In the accompanying drawings, Fig. 1 is a longitudinal sectional view of a sewing machine embodying the present improvements. Fig. 2 is a top plan view of the machine, the front portion of the overhanging arm being broken away and the standard

thereof being shown in section. Fig. 3 is 55 a detail perspective view of the lower spreader supporting means. Fig. 4 is a perspective view, partly in section, of the throat-plate of the machine and particularly illustrating the stitch-retaining finger. 60 Figs. 5 to 10, inclusive, are perspective views illustrating successive positions of the needles and loop-spreaders in the formation of the overseam. Fig. 11 is an enlarged bottom plan view of the needle-holder. 65

Referring to the drawings, the present improvement is embodied in a sewing machine of which the frame comprises a base 1 having a cloth-plate 2 and from which rises a hollow standard 3 of an overhanging bracket-arm 4, terminating in a head 5. Journaled for rotation in suitable bearings provided in the bracket-arm 4 is a main or needle-driving shaft 6 carrying at one end a crank-disk 7 from which projects a crank-pin 8. The crank-pin 8 carries a roller 9 entering a needle-bar reciprocating cam-groove 10 provided in a cam-block 11 clamped by screws as 12 upon a needle-bar 13. The needle-bar 13 is journaled for end-wise reciprocation in suitable bearings provided in the head 5 and carries at its lower end an eye-pointed work-penetrating needle 14 and a thread-enchaining bearded needle 15 disposed in adjustably spaced relation in 85 a vertical plane substantially transverse to the direction of feed of the fabric.

In the present machine, the work-penetrating position of the needle 14 is fixed by securing it directly to the needle-bar by any suitable means. The bearded needle 15 may, however, have a plurality of predetermined paths of operation to form overseams of various widths of bight. To this end the shank of the needle 15 may be inserted in 90 any one of a plurality of apertures 150 formed in a needle-holder 151 and secured upon said holder by a set-screw 152. The needleholder 151 projects laterally from the needle-bar 13, being secured thereupon by 95 means of a set-screw 153.

Also journaled for vertical reciprocation in suitable bearings provided in the head 5 is a spring-pressed presser-bar 16 carrying at its lower end a presser-foot 17. A feeding foot 18 is carried by a feed-bar 19 supported and actuated in any suitable or well known manner, whereby the feeding foot

advances the work past the needles and rises and falls alternately with the presser-foot 17, the feeding foot as usual acting to advance the work in the raised position of the presser-foot. Inasmuch as the particular form of feed-actuating mechanism employed is immaterial, it is deemed unessential to an understanding of the present invention to herein describe in detail the form employed.

10 Cooperating below the work with the needles 14 and 15 is a lower spreader 20, the shank of which is secured by screws as 21 in the socketed lateral arm 22 of a sleeve 23 journaled for oscillatory movements upon a fulcrum-pin 24 suitably secured upon a depending lug 25 on the machine frame. Another lateral arm 26 on the sleeve is apertured for the reception of a stud-screw 27 threaded into the arm 22 and which is embraced by the apertured end of a link 28. The other end of the link is connected by means of a pivot-screw 29 with the lower end of a rock-lever 30 having a plurality of link-connecting apertures, as 31. The rock-lever 30 is secured by means of a screw 32 upon a pivot-pin 33 suitably journaled in the standard 3, the upper end of said rock-lever carrying a roller-stud 34 entering a cam-groove 35 of a cam-cylinder 36 secured upon the main-shaft 6.

15 It will be understood that rotation of the cam-cylinder 36 with the main-shaft 6 will impart rocking movements to the lever 30 which movements are transmitted by the link 28 to the lower spreader 20. By connecting the link 28 with the proper aperture 31 of the rock-lever 30 in conformity with the selected position of the needle 15 in the apertures 150 of the needle-holder, the vibration of the lower spreader has the proper timing and extent of movement essential to produce any one of three substantially different widths of bight of overseam.

20 An upper spreader 37 is disposed above and substantially parallel with the cloth-plate 2 and is adjustably secured by means of a screw 38 upon a grooved seat 39 provided in one arm 40 of a two-armed rocking carrier from which depends a substantially vertical fulcrum-stud 41 preferably integral with the carrier 40. The fulcrum-stud 41 is pivotally supported within an apertured boss 42 and is retained therein by means of a screw 43 threaded into the lower end of the stud 41. The apertured boss 42 projects substantially at right angles from the free end of a horizontal swinging arm 44 of a bellcrank-lever disposed beneath the cloth-plate 2 and having a hub 45 journaled upon a stud-screw 46 threaded into the under side of the cloth-plate. The other arm 47 of the bellcrank-lever 44, 47, is suitably connected to one end of a link 48 of which the opposite end is connected by means of a screw 49 with any one of a plurality of apertures 50

formed in a lateral arm 51, of which the hub 52 is pinned upon a vertical rock-shaft 53. The rock-shaft 53 is journaled for oscillatory movements in suitable bearings provided in the machine frame, endwise movement of said rock-shaft being prevented on one end by the hub 52 and on its opposite end by the hub 54 of another lateral arm 55 suitably clamped upon the rock-shaft. The arm 55 carries a roller-stud 56 entering a second cam-groove 57 in the cam-cylinder 36.

70 Rocking movements are imparted to the carrier 40 upon the swinging arm 44 by connecting the arm 58 of said carrier 40, 58, 80 with one end of a link 59 of which the opposite end is pivoted upon the free end of a lateral arm 60 suitably clamped upon a vertical rock-shaft 61. The rock-shaft 61 is suitably journaled in the machine frame and 85 carries another lateral arm 62 having a roller-stud 63 engaging a third cam-groove 64 provided in the cam-cylinder 36.

80 The upper spreader receives a curvilinear movement in a horizontal plane through the 90 described connections with the cam-grooves 57, 64, the swinging movements of the arm 44 imparting endwise reciprocations to the spreader 37 across the margin of the work and the rocking movements of the carrier 95 40, 58, impart lateral movements to said spreader to seize the needle-thread at the limit of its advancing movement and present a loop of said needle-thread to the bearded needle at the limit of its retracting 100 movement. By connecting the link 48 with the proper aperture 50 of the arm 51 the operation of the upper spreader may be made to conform with the lower spreader 37 and the path of operation of the needle 15 to 105 obtain any one of three different widths of bight of overseam. Consequently, the present machine is readily convertible to produce several substantially different widths of bight of overseam, thereby eliminating the 110 necessity of constructing a machine for each width of bight as was heretofore the case.

115 A circular throat-plate 65 is secured by screws, as 66, in an opening provided therefor in the cloth-plate 2. The throat-plate is itself provided with a substantially rectangular needle-opening 67 having a beveled rear edge 68. Projecting within the opening 67, whereby its upper surface is substantially flush with the upper surface of the throat-plate is a stitch-retaining finger 69 secured to the under side of the throat-plate by means of a screw 70. The free end of this finger is beveled on its under side and is disposed slightly in advance of the beveled edge 68, whereby the loops of thread upon the under side of the fabric will readily feed off the beveled surface of the finger 69 and up over the beveled edge 125 68 upon the throat-plate. The primary 130

function of the finger 69, however, is to prevent distortion of the work by the action of the lower spreader to draw out the needle-thread loop, the lateral stress being absorbed by said finger.

Adjustably secured upon the cloth-plate 2 by means of a screw 71 is a bearded-needle back-guide 72 having a notched free end 73 positioned to engage the rear side of the 10 needle 15 to prevent rearward deflection of said needle under the action of a beard-closing member 74. This beard-closing member 74 has a beard-engaging edge 75 and is secured by screws as 76 upon an edge-guide 15 77 adjustably secured by screws as 78 and an elongated slot 79 of said edge-guide upon the cloth-plate 2. The slot 79 is somewhat wider than the screw-shanks passing therethrough whereby the edge-guide may be adjusted in transverse directions to determine the width of the overseam as well as to correctly position the beard-engaging edge 75 of the member 74.

In the operation of the machine, the eye-pointed needle 14 penetrates the work and the bearded-needle 15 reciprocates beyond the work-margin. Referring more particularly to Figs. 5 to 10, inclusive, the overseam is shown as being formed upon the work *w*, the 20 needles 14 and 15 being at the top of their stroke in Fig. 5 and the bearded end of the needle 15 just clearing the back-guide 72. In this position the lower loop-spreader 20 is being retracted and the upper loop-spreader 37 has seized the thread carried by the eye-pointed needle 14 and has partially completed its movement to present an upper loop of thread *a* to the bearded needle 15 while the work is being fed past the 30 needles. In Fig. 6 the needles have partially descended and the upper spreader 37 has completed its loop-presenting movement whereby one limb of the loop *a* is passed under and behind the needle 15 while the other limb thereof remains in front of the 40 needle 15 due to the angle of said front limb from the spreader 37 to the eye of the needle 14. In Fig. 7 the needles have completed their descending movement and the lower spreader 20 its retracting movement, while the upper spreader is again advancing above the work.

As the needles now rise, a lower loop of thread *b* is cast by the needle 14 which is seized by the lower spreader 20 and presented to the bearded needle 15 below the work as illustrated in Fig. 8. The lateral stress produced by the drawing out of the lower loop *b* is absorbed by the stitch-retaining finger 69 to avoid distortion of the work. The needles continuing to rise, the beard 15' of the needle 15 engages the end 75 of the block 74 and is closed by reason of the fact that the back-guide 72 opposes any 50 yield of the needle 15. This position is il-

lustrated in Fig. 9 and it will be apparent that as the needles continue to rise the closed beard of the needle 15 will readily slip through the upper loop *a* and through a previously formed lower loop *b* about the 60 shank of the needle 15, as shown in Fig. 10, thereby enchaining the lower loops *b* at the margin of the work while the upper loop is held by the enchain lower loops. It is of course to be understood that also during the 70 descending movement of the needle 15 is the beard 15' closed by engagement with the block 75, but this occurs just after the lower loop *b* has slipped past the beard 15' upon the shank of the needle 15.

Having thus set forth the nature of the invention, what we claim herein is:—

1. In an overedge sewing machine, the combination with stitch-forming mechanism including a thread-carrying eye-pointed needle and a thread-enchaining bearded needle reciprocating substantially in unison in adjustably spaced paths, and loop-spreaders cooperating with said needles to produce an overseam of substantially uniform width of 80 90 bight, of means for actuating said loop-spreaders including connections permanently mounted in the machine convertible to produce substantially different widths of bight of overseam.

2. In a stitch-forming mechanism for overedge sewing machines, the combination with an eye-pointed work-penetrating needle, an over-the-edge operating bearded needle, means for reciprocating said needles, and a lower spreader for presenting a thread-loop below the work from said eye-pointed needle to said bearded needle, of an upper spreader for conducting a thread-loop above the work from said eye-pointed needle to 100 said bearded needle, a swinging arm, a pivotal support for said arm, a pivotal support for said upper spreader upon said arm, a rotary cam, operative connections between the cam and said arm for vibrating the latter, and means including another rotary cam for rocking said upper spreader upon said arm.

3. Stitch-forming mechanism for overedge sewing machines comprising in combination, a thread-carrying eye-pointed needle and a thread-enchaining bearded needle, means for reciprocating said needles substantially in unison, upper and lower spreaders disposed respectively above and below the work for carrying thread-loops from the eye-pointed needle to the bearded needle, means for actuating said lower spreader, a rocking carrier sustaining said upper spreader, a swinging arm upon which said carrier is fulcrumed, a rotary shaft, and actuating connections independent of each other between said shaft and the swinging arm and said rocking carrier.

4. In a sewing machine, the combination 130

with a cloth-plate, an overhanging arm, and a rotary shaft journaled in said overhanging arm, of overedge stitch-forming mechanism comprising a thread-carrying eye-pointed needle and a thread-enchanting bearded needle, operative connections with said rotary shaft for reciprocating said needles substantially in unison, upper and lower spreaders disposed respectively above and below said cloth-plate for carrying thread-loops from the eye-pointed needle to the bearded needle, a vibratory carrier for said lower spreader fulcrumed beneath the cloth-plate, means for vibrating said carrier, a rocking-carrier supporting said upper spreader, a swinging arm pivotally supported beneath said cloth-plate upon which said rocking carrier is fulcrumed, means for swinging said arm, and means for rocking said carrier upon said arm.

5. In a sewing machine, the combination with a cloth-plate, an overhanging arm, and a rotary shaft journaled in said overhanging arm, of overedge stitch-forming mechanism comprising a thread-carrying eye-pointed needle and a thread-enchanting bearded needle, operative connections with said rotary shaft for reciprocating said needles substantially in unison, upper and lower spreaders disposed respectively above and below said cloth-plate for carrying thread-loops from the eye-pointed needle to the bearded needle, a vibratory carrier for said lower spreader

fulcrumed beneath the cloth-plate, means for vibrating said carrier, a rocking carrier for said upper spreader, a bellcrank-lever, a pivotal support for said lever beneath the cloth-plate, a pivotal support for said carrier upon said lever, a cam carried by said shaft, operative connections between said cam and one arm of said lever to rock the latter upon its fulcrum, and means for rocking said carrier upon the other arm of said lever.

6. In an overedge sewing machine, in combination, adjustably spaced eye-pointed and bearded needles, means for reciprocating said needles, upper and lower loop-spreaders for carrying thread-loops from said eye-pointed needle above and below the work for enchantment by said bearded needle at the margin of the work, means for vibrating said lower spreader including connections convertible to vary the path of movement of said lower spreader a predetermined extent, means for actuating said upper spreader in substantially transverse directions including connections convertible to vary the path of movement of said upper spreader a predetermined extent in one of said directions.

In testimony whereof, we have signed our names to this specification.

ALFRED GRIEB.
JOSEPH F. PALME.
